UNITED STATES PATENT OFFICE.

AMSEY P. LLOYD, OF ELKHART, INDIANA.

WOOD BINDER.

Application filed February 21, 1923. Serial No. 820,535.

To all whom it may concern:

Be it known that I, AMSEY P. LLOYD, a citizen of the United States, residing at Elkhart, in the county of Elkhart, in the State 5 of Indiana, have invented a new and useful Improvement in Wood Binders, of which the following is a specification, reference being had to the accompanying drawing, forming a part thereof.

10 In many of the uses of timbers, such as for bridge trestles, railroad ties and crib-work, it has long been known that exposure to the elements, particularly on the end of a log or timber, will result in cracking or 15 checking. This is particularly true of railroad ties, which, in a very short time after being cut and prepared for use, will check or split at the end, such a split eventually extending into the tie to such an extent as 20 to make it unsafe and often useless long before the tie is rotted or decayed in the usual manner. Various devices have been tried with the idea of drawing the ends of ties, as well as other timbers, together either 25 before or after a crack has occurred. Nearly all of these have a tendency to augment the crack or split, either in the manner of application or in their construction. Such a device, to be successful must be simple in 30 construction as well as in application, must be comparatively inexpensive to make and should be applicable without danger of splitting the wood.

35 In the accompanying drawings, I have shown several embodiments of the invention. In this showing:

Figure 1 is a perspective view of a railroad tie showing the invention applied,

40 Figure 2 is a central vertical longitudinal sectional view,

Figure 3 is a front elevation of the binder removed,

Figure 4 is a detail sectional view on line 4-4 of Figure 3,

45 Figure 5 is a front elevation of another form of the invention, and,

Figure 6 is a detail sectional view on line 6-6 of Figure 5.

50 Referring to the drawings, the reference numeral 1 designates a railroad tie or similar timber. The binder forming the subject matter of the present invention consists of a bar 2 of steel or iron, which is substantially wedge shaped in transverse

cross-section, as shown in Figure 2 of the 55 drawings. The angle of the point of the wedge is very acute to permit the binder to be readily driven into the end of a tie. The ends of the bar are split for a convenient distance and each of the split members 3 is then curved outwardly and rearwardly, care being taken not to bend the split members at an angle, as such angles have a tendency to split the wood when the binder is inserted. Each of the split members will have a cross-section of a half wedge, as shown in Figure 4 of the drawings.

In the form of the invention shown in Figures 5 and 6 of the drawings, a bar 4 is employed of suitable shape to provide end 70 members 5 of wedge shaped cross-section, as shown in Figure 6.

The binder is laid on the end of a tie or log, with the wedge point next to the surface, and driven in until the point of the 75 wedge has penetrated the wood and the top or back of the binder is flush with the surface thereof. This may be accomplished with a sledge or hammer, requiring no skill and no apparatus, and when the binder is 80 so applied it will firmly hold the fibre of the log or tie together so that it will not split in the usual manner, and the life of the timber, log or tie will be greatly extended. The exposure to moisture in the 85 wood or from the outside has a tendency to oxidize the steel or iron, thus holding it more firmly in place.

I do not limit my invention to any particular size or relative dimensions, so long 90 as the general shape is preserved of a bar having a wedge shaped cross section with two rearwardly curved members on each end, nor do I limit its use to the preservation 95 of wood from cracking, but it may be used to hold together two or more logs or timbers in structural work.

What I claim as my invention is:

1. A wood binder comprising a bar having a substantially wedge shaped cross section, having two rearwardly curved and structurally integral members on each end, each of said members having a substantially wedge shaped cross section. 100

2. A wood binder comprising a long and 105 relatively narrow body having a substantially wedge shaped cross section; two structurally integral members on each end of said

body, each of said members also having a wedge shaped cross section of substantially the same nature as the cross section of said body, and each of said members being curved 5 outwardly and rearwardly from said bar.

3. A wood binder comprising a bar having a substantially wedge shaped cross sec-

tion, the end of said bar being provided with two rearwardly curved and structurally integral members, each of said members having a substantially wedge-shaped cross section. 10

AMSEY P. LLOYD.
